Primary Examiner — Kevin Rudzinski(74) *Attorney, Agent, or Firm* — Jackson IPG PLLC;
Demian K. Jackson**CLAIM**

I claim the ornamental design for a permanent wave tool, as shown and described.

DESCRIPTION

FIG. 1 is a perspective view of a permanent wave tool showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in FIGS. 1-7 illustrate unclaimed portions of the permanent wave tool and form no part of the claimed design.
